(57) **CLAIM**

The ornamental design for an interproximal dental tool, as shown and described.

DESCRIPTION

FIG. 1 is a perspective view of the interproximal dental tool with an abrasive blade showing my new design;

FIG. 2 is a front elevational view of the interproximal dental tool shown in FIG. 1;

FIG. 3 is a top view of the interproximal dental tool shown in FIG. 1;

FIG. 4 is a left side view of the interproximal dental tool shown in FIG. 1;

FIG. 5 is a bottom view of the interproximal dental tool shown in FIG. 1;

FIG. 6 is a back view of the interproximal dental tool shown in FIG. 1; and,

FIG. 7 is a right side view of the interproximal dental tool shown in FIG. 1.

The broken lines shown in the drawings are included for the purpose of illustrating structural environment and form no part of the claimed design.
